COMBINED GAME CHIP RACK AND ASH
TRAY OR THE LIKE

Meyer Greitzer, Beverly Hills, Calif.

Application June 17, 1949, Serial No. 3,339

Term of patent 7 years

(Cl. D34—13)

To all whom it may concern:

Be it known that I, Meyer Greitzer, a citizen of the United States of America, residing at Beverly Hills, in the county of Los Angeles and State of California, have invented a new, original Design for Combined Game Chip Rack and Ash Tray or the like, of which the following is a specification; reference being had to the accompanying drawing, forming a part thereof.

Fig. 1 is a plan view of a combined game chip rack and ash tray or the like, embodying my new design,

Fig. 2 is a side elevational view thereof, and
Fig. 3 is an end view thereof.

I claim:

The ornamental design for a combined game chip rack and ash tray or the like, as shown.

MEYER GREITZER.
